UNITED STATES PATENT OFFICE

GEORGE SWALLOW, OF SALT LAKE CITY, UTAH

HERNIA TRUSS

Application filed October 19, 1926. Serial No. 142,585.

This invention relates to trusses, particularly hernia trusses, and is in the nature of an improvement on the truss of the invention set forth in my Patent No. 1,567,769, granted December 29, 1925.

The object of the invention is to provide a truss which is adapted to the treatment of hernia in various portions of the abdomen, and which will enhance the comfort of the wearer by being capable of adjustment in a number of different ways.

The invention consists in a truss composed of a plurality of members or straps, formed preferably of elastic webbing, so connected and provided with attaching means as to be adjusted to the body of the wearer in a manner to support a hernia with equal effectiveness and comfort regardless of the bodily positions or postures assumed by the wearer, as I will proceed now to explain and finally claim.

In the accompanying drawings illustrating the invention, in the several figures of which like parts are similarly designated, Figure 1 is a perspective of the truss viewed from the back. Fig. 2 is a front view showing the truss in one mode of adjustment upon the body of a wearer, the outline of the body being indicated by broken lines. Fig. 3 is a back view similar to Fig. 2. Fig. 4 is a front view similar to Fig. 2 but illustrating another mode of adjustment. Fig. 5 is a back view of the arrangement shown in Fig. 4. Fig. 6 is a fragmentary front view showing a still further mode of adjustment.

Referring particularly to Fig. 1, it will be seen that the truss consists of a number of members, formed preferably of elastic webbing, and provided with adjusting and securing devices, such as buckles and buckle engaging members. The main members 1 are crossed as at 2 and suitably secured at this point as by stitching, as shown. At their lower ends the members 1 are looped as at 3, to form leg-embracing members, by passing their ends through slides 4 suitably attached to the members, as shown. The ends of these members are provided with buckles 5. The other ends 6 of the members 1 are free, and have attached to them by stitching, or other-

wise appropriately, straps 7. Secured at 8 to the main members, intermediate their point of intersection 2 and the slides 4, are support members 9, provided adjacent to their point of attachment 8 with buckles 10, and having at their free ends buckles 11 removably attached by means of loops formed in the ends of the members and secured by means of separable fasteners 12 or the like.

The main members 1 are furnished with eyelets or loops 13 and 14 and tapes 15 for a purpose hereinafter appearing.

From the foregoing it will be seen that the truss is constructed in substantially the same manner as that of my patent hereinbefore mentioned, but with certain improvements and modifications.

Obviously the truss may be adjusted upon the body of the wearer in the same manner as that of my patent, or modifications in the mode of its adjustment to accommodate various conditions and bodily characteristics may be made, as will now be explained.

In the arrangement illustrated in Figs. 2 and 3, the truss is adjusted as follows:— First the legs are passed through the loops 3, the slides 4 permitting automatic adjustment of the size of the loops to fit the legs. Then the members 1 are adjusted along the back, as shown in Fig. 3, the point 2 of their crossing preferably falling just between the small of the back and the shoulder-blades. The free ends 6 are then passed over the shoulders so that they extend downwardly over the chest and at the sides of the wearer. The buckles 5 carried by the loop-forming ends of the members 1 are then secured to the ends 6. The support members 9 are then drawn around from the back, crossed over the abdomen, as at 16, passed around the thighs from front to back, thence through the crotch from back to front, and their free ends carrying the buckles 11 secured to the straps 7. In order to maintain the leg-encircling portions of the members 9 in a comfortable position and prevent them from working downward the tapes 15 may be run through and secured to the loops 13.

This arrangement of the various members varies from that disclosed in my patent here-

inbefore mentioned in that instead of crossing the free ends 6 of the members 1 over the chest, they are so arranged as to extend downwardly at the sides of the body. This may be found to be more comfortable for some persons than the patented arrangement, but, obviously, the truss of the present invention may be worn with the ends 6 of the members 1 crossed over the chest, as shown in Fig. 4. 5
10 As will be seen, particularly by reference to Figs. 3 and 5, the attachment of the support members 9 to the main members 1 at the point 8 removes these members from contact with the back of the wearer and makes it 15 possible to support a hernia located much lower in the abdomen than was possible with the truss of my patent.

When it is desired to treat a hernia located higher in the abdomen than can be treated 20 with the truss adjusted as in Figs. 2 and 3, the adjustment shown in Figs. 4 and 5 may be employed. In this adjustment, the loops 3 and main members 1 are arranged in the same manner as just described, either with the ends 25 3 extending downwardly at the sides, as in Fig. 2 or crossed over the chest, as in Fig. 4. But the support members 9, instead of being run through the crotch, are made to encircle the abdomen and hips, their ends being freed 30 of the buckles 11 by opening the loops formed by the separable fasteners 12, and then secured to the buckles 10. In this adjustment of the members 9 the tapes 15 are connected with the loops 14, as shown in Fig. 5, to support the members in proper position. 35

If it is desired to cover a still greater area of the abdomen the support members 9 may be arranged as shown in Fig. 6 by removing the buckle 11 from only one of these members 40 and then securing the ends of the two members together by connecting this end with the buckle 11 carried by the other member. In this arrangement the support members 9 encircle the abdomen and extend well down over the lower portion thereof. 45

If localized pressure is desired a pad of gauze, felt or other suitable material may be inserted under the support members 9 at the desired point, as indicated in broken lines at 50 17 in Figs. 2, 4 and 6.

The support members 9 are the main truss or pressure-exerting members and taken together form, in effect a truss member encircling the body, whether adjusted as in Figs. 52 and 3, 4 and 5 or 6. Where they pass over the abdomen they exert a pressure sufficient 55 to support or compress the hernia, and, no matter what position the wearer may assume, this pressure will be exerted at all times, due 60 to the elastic nature of the webbing and its ability, owing to the arrangement of the various members, to adjust itself to the contours of the wearer's body.

The leg-embracing members 3 serve to prevent the truss from riding up on the abdo-

men due to bodily movements of the wearer, and the support of the members 1 by the shoulders of the wearer will prevent the truss from dropping down.

The loops 13 and 14 and cooperating tapes 70 15, when properly connected will prevent uncomfortable separation of the members 9 and loops 3 and possible pinching of the flesh between them, when worn as in Figs. 2 and 3, and will hold the members 9 in proper abdomen-encircling position when worn as in Figs. 75 4, 5 and 6.

The members 9 will be held at all times 80 in the same position relatively to the abdomen by these several means of support, and, in addition to the constant effective pressure exerted by them, will be comfortable because they are always in place.

The truss may be worn either with or without the ordinary belt or corset, as desired. 85

I am aware that various trusses have been devised having abdominal bands or belts and means for holding them by means of shoulder braces and leg straps in proper position, but I do not know of any device similar to mine 90 which may be worn in a variety of ways for supporting hernias of the upper or lower abdomen, and which lends itself so readily to adjustment to enhance the comfort and convenience of the wearer, and to give him that comfortable well-supported feeling so sought by those suffering from hernia. 95

Various changes are contemplated as within the spirit of the invention and the scope of the following claim. 100

What I claim is:—

In a hernia truss, main members encircling the legs of the wearer adjacent to the crotch and extending upwardly along the back and over the shoulders of the wearer and connected to their leg-embracing portions in front, support members carried by said main members and encircling the body of the wearer at the abdomen, buckles carried by said support members adjacent to their connections with the main members, and buckles carried at the ends of said support members, the buckles at the ends being removable so that the ends may be connected to the buckles adjacent to the main members to form a relatively narrow abdominal band, and one of said end buckles serving as a means to connect the ends of the two support members together to form a relatively wide abdominal band. 110

In testimony whereof I have hereunto set 115 my hand this 15th day of October A. D. 1926.

GEORGE SWALLOW.
